LAWN SPRINKLER

John D. Beinert, New York, N. Y., assignor to Melnor Metal Products Co., Inc., Long Island City, N. Y., a corporation of New York

Application November 18, 1953, Serial No. 27,655

Term of patent 14 years

(Cl. D91—1)

FIG. 1.

FIG. 2.

FIG. 3.

FIG. 4.

FIG. 5.

To all whom it may concern:

Be it known that I, John D. Beinert, a citizen of the United States and a resident of New York city, county and State of New York, have invented a new, original, and ornamental Design for a Lawn Sprinkler, of which the following is a specification, reference being had to the accompanying drawings forming a part thereof, in which:

Fig. 1 is a perspective view of a lawn sprinkler showing my new design;

Fig. 2 is a side elevational view thereof;

Fig. 3 is a plan view thereof;

Fig. 4 is a rear end elevational view thereof; and

Fig. 5 is a front end elevational view thereof.

I claim:

The ornamental design for a lawn sprinkler, as shown.
